(57) **CLAIM**

The ornamental design for a slider, as shown.

DESCRIPTION

FIG. 1 is a front elevational view of a slider showing our new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is another perspective view thereof;

FIG. 9 is another perspective view thereof;

FIG. 10 is another perspective view thereof;

FIG. 11 is another perspective view thereof;

FIG. 12 is another perspective view thereof;

FIG. 13 is another perspective view thereof;

FIG. 14 is another perspective view thereof;

FIG. 15 is another perspective view thereof; and,

FIG. 16 is another perspective view thereof.

1 Claim, 16 Drawing Sheets
